LEVER FOR TRACK SCALES

Alfred Bousfield, St. Johnsbury, Vt., assignor to
E. and T. Fairbanks and Company, St. Johnsbury, Vt., a corporation of Vermont

Application May 25, 1931. Serial No. 539,892

14 Claims. (Cl. 265—71)

The present invention relates to improvements in weighing scale levers, particularly to longitudinal extension levers for track scales.

This invention is broadly disclosed in my co-pending application Serial No. 384,057, Track scales, filed Aug. 7, 1929.

In track scales the levers are necessarily subjected to heavy loads and stresses, when weighing operations are being performed and the levers consequently are heavily and ruggedly built in order to properly withstand the use for which they are designed.

Therefore, an important object of the invention is to provide an efficient, built up lever of girder or I-beam construction adapted to carry the lever fulcrum and load supports and provided with openings in the body and butt end of the web, in which are mounted a lever fulcrum block and a load bearing block, each having seated therein and supporting a plate-fulcrum.

Another object is to provide the lever with reinforcing means at certain bearing points where stress or load is applied, such as under the load pivot block.

Another object is to provide similar reinforcing means in the butt end of the lever above the fulcrum bearing block.

Another object is to provide reinforcing means on each side of the web of the girder beam above the lever fulcrum block and below the load bearing block, so as to compensate for any possible weakening of the adjacent metal due to cutting openings in the web for holding the support blocks.

Still another object is to provide the tip end of the lever with an extension nose iron adapted to carry a plate-fulcrum mounted in a block carried thereby.

In order that the nature of my invention may be fully understood, I have illustrated certain embodiments of the invention in the accompanying drawing, in which,—

Figure 1 is a longitudinal elevation of a lever, broken away in its center section, showing a preferred form of my invention.

Figure 2 is an end view on the lines 2—2 of Fig. 1 showing the fulcrum end of the lever with the plate fulcrum and its supporting block.

Figure 3 is a vertical cross section on the line 3—3 of Figure 1 showing the load receiving section of the lever with the plate-fulcrum mounted in its block and reinforcing plates on the girder beam flanges.

Figure 4 is a vertical cross section on the line

4—4 of Fig. 1 showing the nose iron attached to the web of the girder beam forming the lever.

Referring to the drawing 1 designates a lever formed of a girder or I-beam 2, provided with an opening 3, preferably rectangular, in the web 4 at the butt end of the lever. Adjacent to the opening 3 the web 4 is provided with a similar rectangular opening 5 located in a substantially central position therein.

Above the opening 3 on each side of the web 4 is riveted and welded an inverted L-shaped angle-iron or support 6 with its flange 7 in line with the upper edge 8 of the opening 3 and having its upper edge 9 joined by a welded metal filler 10 to the upper flange 11 of the girder beam 2. A vertical plate 12 is mounted in the center of each angle-iron 6 and is welded to the web of the angle-iron between the flange 7 of the angle-iron and the upper flange 11 of the girder beam.

Seated in a reduced portion 13 of the opening 3 and disposed transversely of the girder beam 2 is a lever fulcrum block 14, which is first adjusted to its proper operative position and held therein by bolts 15, secured to the flanges 7 and then welded to the flanges and the web 4. The lever fulcrum block 14 thus forms a fulcrum plate support for a plate fulcrum 16 secured by bolts to the block at the fulcrum point of the lever.

In a similar manner an inverted L-shaped angle-iron or support 17 is riveted and welded on each side of the web 4 below the opening 5 having its flange 18 flush with the lower edge 19 of the opening 5, while the lower edge of the angle-iron is joined by a welded metal filler 20 to the lower flange 21 of the girder beam. Disposed in the center of each angle-iron 17 is a vertical plate 22, which is welded to the web of the angle-iron between its flange 18 and the lower flange of the girder beam.

A load bearing block 23 is mounted transversely of the girder beam 2 in the opening 5 and is supported on the flanges 18 of the opposed angle-irons 17, on which the block 23 is initially adjusted to its proper position and then fastened thereto by bolts 24, after which it is welded to the flanges and the web 4. A plate-fulcrum 25 is fastened by bolts to the load bearing block 23, which thus serves as a support therefor.

Attached to the upper flange 11 and the lower flange 21 of the girder beam 2 are reinforcing plates 26 and 27 respectively, which are riveted and welded to the flanges 11 and 21, in a position above and below the load bearing block 23, each

plate being disposed with its center in vertical alignment with the center of the plate-fulcrum 25 carried by the load bearing block 23. A longitudinally extending nose iron 28, formed of opposed angle-irons 29, riveted and welded to the upper part of the web 4 at the tip end of the girder beam 2, carries at its free end on the under side a bracket 29a provided with an adjusting screw 29b adapted to co-act with and move to the proper position a bearing block 30 slidably mounted on the angle-irons 29, in which bearing block there is mounted a plate-fulcrum 31 operatively connected to the transverse extension lever of the scale, not shown. An inclined edge 32 on the lower part of the tip end of the girder beam affords clearance for the lever as it moves under influence of the load.

While I have shown a preferred embodiment of my invention it is evident that modifications of the invention may be made that will come within the scope of the invention and, therefore, I do not desire to limit the invention to the exact form of construction shown and described herein.

I claim:—

- 25 1. A lever for track scales formed of a girder beam and having openings in its web, and reinforcing means adjacent to one end of each opening, supporting a lever fulcrum support and a load support, the said reinforcing means comprising angle-supports attached to the opposite side of the girder beam web and supported on the flange of the girder beam.
- 30 2. A lever for track scales formed of a girder beam and having openings in its web, and reinforcing means adjacent to one end of each opening, supporting a lever fulcrum support and a load support, comprising inverted L-shaped angle-supports secured to the opposite sides of the girder beam web and supported on the flange of the girder beam.
- 35 3. A lever for track scales formed of a girder beam and having openings in its web, and reinforcing means adjacent to one end of each opening, supporting a lever fulcrum support and a load support, and comprising inverted L-shaped angle-supports secured to the opposite sides of the girder beam web and provided below with a vertical centrally disposed plate secured to the said girder beam web.
- 40 4. A lever for track scales formed of a girder beam and having openings in its web openings, in which are mounted a lever fulcrum support and a load support, and reinforcing means secured to the upper and lower flanges of the girder beam in a position above and below the said lever fulcrum and load supports respectively.
- 45 5. A lever for track scales formed of a girder beam and having openings in its web at the butt end and in a substantially central position respectively, a lever fulcrum support and a load support mounted in its respective opening, inverted L-shaped opposed angle-supports mounted on the web of the girder beam below an end of each opening, and a lever fulcrum support and a load support mounted in its respective opening and welded to the said web and angle-supports.
- 50 6. A lever for track scales formed of a girder beam and having openings in its web at the butt end and in a substantially central position respectively, a lever fulcrum support and a load support mounted in its respective opening, each transversely disposed in its respective opening and reinforcing plates attached to the upper and lower flanges of the said girder beam and disposed above and below the said load support.

7. A lever for track scales formed of a girder beam and having openings in its web, and a lever fulcrum support and a load support mounted in its respective opening, each comprising an angle-iron welded to the web and provided with a vertical, centrally disposed plate welded to the angle-iron and the adjacent flange of the girder beam.

8. A lever for track scales formed of a girder beam and having openings in its web, a lever fulcrum support and a load support mounted in its respective opening, each comprising an angle-iron welded to the web and provided with a vertical, centrally disposed plate welded to the angle-iron and the adjacent flange of the girder beam, and a welded metal filler joining the edge of each angle-iron to the adjacent flange of the girder beam.

9. A lever for track scales formed of a girder beam and having in its web openings, in which are mounted a lever fulcrum support and a load support, a plate-fulcrum mounted in the said load support, and a reinforcing means secured respectively to the upper and lower flanges of the girder beam in a position above and below the said load support and disposed with its center in vertical alignment with the center of the plate-fulcrum carried by the said load support.

10. A lever for track scales formed of a girder beam and having in its web openings, in which are mounted a lever fulcrum support and a load support, a plate-fulcrum mounted in each of said lever fulcrum and load supports, and a reinforcing plate secured and welded respectively to the upper and lower flanges of the girder beam at a point above and below the said load support and having its center in vertical alignment with the center of the plate-fulcrum carried by each of the said lever fulcrum and load supports.

11. A lever for track scales formed of a girder beam, a longitudinally extending nose iron disposed at the tip end of the said girder beam and formed of opposed angle irons secured and welded to the upper part of the web of the girder beam, a bearing block mounted on the under side of the said angle irons and having a plate-fulcrum fastened thereto, and a bracket secured to the under side of the angle-irons carrying adjustable means co-operating with the said bearing block and adapted to move the said bearing block and its plate fulcrum to the proper position.

12. A lever for track scales formed of a girder beam and having openings in its web, a lever fulcrum support and a load support mounted in its respective opening, and reinforcing means for the said supports centrally and vertically disposed in relation thereto and supported on each flange of the girder beam.

13. A lever for track scales formed of a girder beam and having openings in its web, a lever fulcrum support and a load support mounted in its respective opening, and reinforcing means for the said supports comprising opposed angle-irons welded to the web of the girder beam, centrally and vertically disposed in relation thereto and supported on each flange of the girder beam.

14. A lever for track scales formed of a girder beam and having openings in its web, a lever fulcrum support and a load support mounted in its respective opening, plate-fulcrums secured to the lever fulcrum support and the load support, and reinforcing means for the said supports centrally and vertically disposed in relation thereto and supported on each flange of the girder beam.
